CLAIM

The ornamental design for a refrigerator management display screen with animated graphical user interface, as shown and described.

DESCRIPTION

FIG. 1 is a front view of a refrigerator management display screen with animated graphical user interface showing a first image of our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof; and,

FIG. 10 is a tenth image thereof.

The outermost broken lines show a refrigerator management display screen, and form no part of the claimed design. The evenly spaced broken lines in the figures show portions of the graphical user interface that form no part of the claimed design. The curved unevenly spaced broken line arrows in FIGS. 1 and 9 form part of the claimed design.

The appearance of the animated image transitions between the images shown in FIGS. 1-10. The process or period in which one image transitions to another forms no part of the claimed design.
